EUGENE LAMAR SMITH, OF OAK CLIFF, TEXAS, ASSIGNOR OF TWO-THIRDS TO GEORGE F. CHILDRESS, OF WILLS POINT, TEXAS.

SWITCH-CORD PLUG.

No. 886,262

Specification of Letters Patent.

Patented April 28, 1908.

Application filed September 1, 1906. Serial No. 332,958.

To all whom it may concern:

Be it known that I, EUGENE LAMAR SMITH, a citizen of the United States, and a resident of Oak Cliff, in the county of Dallas and State 5 of Texas, have invented a new and Improved Switch-Cord Plug, of which the following is a full, clear, and exact description.

This invention relates to a new and improved plug adapted to be attached to cords 10 and used in connection with the common form of telephone switchboard, and comprises means whereby the plug may be inserted within a vertical switchboard and the cord relieved from all strain due to its bending at a point at which it is attached to the 15 plug.

My improved plug is made of two parts secured together by a ball and socket, joined so that when one part of the plug is inserted in a 20 vertical switchboard the other part of the plug may turn at an angle without breaking the connection or straining the wire. By this improved joint the one portion of the plug may be rotated a short distance in respect to the other, so that the cord may be relieved of strain due to a slight twisting as 25 the plug is inserted within the switchboard.

Reference is to be had to the accompanying drawings forming a part of this specification, in which similar characters of reference 30 indicate corresponding parts in all the figures, in which

Figure 1 is a side elevation of my complete plug having a portion of the cord attached thereto; Fig. 2 is an enlarged central longitudinal section through my improved plug; Fig. 3 is an enlarged side elevation of the parts constituting the socket; Fig. 4 is an enlarged central longitudinal section through 40 the socket member with one terminal of the plug attached thereto; and Fig. 5 is an enlarged cross section substantially on the line 5—5 of Fig. 2.

My improved plug may be made of any 45 suitable design to accommodate it to the different designs of switchboards now in use, and the terminals of the plug may be arranged in many different manners, but the plug substantially comprises two members 50 secured together by a ball and socket joint, and in the specific form of my invention which I have illustrated in the drawings, the socket member is carried by the portion of the plug inserted within the switchboard,

while the ball portion is carried on the end of 55 the cord.

The ball 1 is formed integral with the head 2 on the end of a cord and is separated therefrom by a short hollow neck 3. The head 2 may be secured to the ends of the wires of the 60 cord 4 in any suitable manner, as for instance, extending each of the wires through insulating casings 5 and 6 and connecting one of these wires to the head by a suitable terminal connection 7, while the other is entirely insulated from the head and adapted to be secured to the wire extending to the tip of the 65 plug, as will be hereinafter described. The socket member of the plug is formed from a hollow cylinder split longitudinally into two 70 parts 8 and 9 and provided with a smoothly polished socket 10, at one end thereof, adapted to exactly fit the outer surface of the ball 1.

The two parts 8 and 9 are rigidly held together after the ball is inserted within the 75 socket and any suitable means for so holding them may be employed, although I preferably provide bolts 11 at the socket end and bolts 12 at the opposite end, the heads of all of which fit within countersunk openings so 80 that no part projects beyond the surface. If desired, a notch or lug 13 may be provided on one of the parts adapted to fit into a similarly shaped recess on the other part and keep the 85 two in perfect alinement.

Secured to the end of the socket member at the end opposite to the socket, is a short tube 14, through the edges of which extend the bolts 12 so that the tube is rigidly held in place; but the bolts 12 do not extend through 90 the inner surface of this tube. Within the tube 14 is a bar 15 separated therefrom by suitable insulating material 16 and terminating within the socket member in the form of an enlarged head 17, which also is insulated 95 from the socket member. The rod 15 has a tip 18 secured to its outer end by means of a screw 19, but the tip and screw are carefully insulated from the tube 14. An insulated conductor 20 connects the enlarged head 17 100 with the terminal of the wire 5 within the head and secured to the cord, and this wire passes through the hollow ball 1 and neck 3, both of which are rounded on their inner sides so that no sharp edges are present to injure the insulated wire or destroy the insulation. The socket member has a portion of 105 one of the parts cut away to form an opening

21, so that the attachment of the wire 20 with the enlarged head 17 may be exposed and adjusted at will, while this opening is normally closed by a sleeve 22 surrounding 5 the major portion of the socket member and formed of any suitable material.

To limit the motion of the ball in respect to the socket, I may, if desired, provide the inner wall of the socket with a recess 23 adapted 10 to receive a pin or stud 24 carried by the ball. The size of the recess may be varied at will and the contact of the pin or stud with the side of the recess will prevent further movement of the ball and socket in respect 15 to each other.

The wire 5 of the cord is connected to the switchboard by means of the insulated terminal within the head, the wire 20, head 17, rod 15, screw 19 and tip 18, while the wire 6 20 of the cord is in electrical contact with the head 2 and the current passes through the parts forming the ball and socket and through the remainder of the socket member to the tube 14. Upon inserting the plug 25 within the switchboard, the tip 18 and tube 14 contact with the two terminals within the switchboard in the ordinary manner.

It is evident that the particular form of the terminals and the specific structure of the 30 plug does not constitute the essence of my invention, as various changes may be made in the details without departing from the spirit of the invention.

Having thus described my invention, I 35 claim as new and desire to secure by Letters Patent:

1. A device of the class described, comprising a switch cord and a switch cord plug movable in respect to each other, the switch 40 cord being provided with a hollow ball secured thereto by a hollow neck and the

switch cord plug being provided with a socket adapted to receive said ball, said socket member being formed of two sections rigidly secured together to hold the ball within the 45 socket, a cylindrical casing inclosing said sections, and a wire extending through said hollow ball and socket and insulated from both and one of said sections being provided with an opening adjacent the end of said 50 wire and normally covered by said casing.

2. A device of the class described, comprising a switch cord and a switch cord plug, the switch cord being provided with a hollow ball secured thereto by a hollow neck and the 55 switch cord plug being provided with a socket adapted to receive said ball, said plug being formed of two semi-cylindrical members rigidly secured together to hold the ball within said socket, and a cylindrical casing 60 surrounding said plug.

3. A device of the class described, comprising two members movable in respect to each other, a hollow ball carried by one of said members, a socket carried by the other 65 65 of said members and adapted to receive said ball, said socket member being formed of two sections secured together to retain the ball within the socket and one of said sections having an opening therein, a casing inclosing 70 said sections and normally covering said opening, and a wire extending through said ball and socket and terminating within said socket member adjacent the said opening.

In testimony whereof I have signed my 75 name to this specification in the presence of two subscribing witnesses.

EUGENE LAMAR SMITH.
